BANDAGE PACKAGE

Lewis D. Abbott, New York, N. Y.

Application February 17, 1955, Serial No. 488,762

2 Claims. (Cl. 206—63.2)

The present invention relates to improvements in surgical dressings, and it relates more particularly to an improved surgical dressing and a protective envelope therefor which may be opened simply and easily to permit the application of the surgical dressing at any desired position.

The present application is a continuation-in-part of co-pending application Serial No. 440,170, filed June 29, 1954, and relating to a bandage package, now matured into U. S. Patent No. 2,752,038, issued June 26, 1956.

It has long been conventional to package surgical dressings individually in order to protect them from external contamination before application. In recent years, it has become a common practice individually to package a strip of adhesive tape carrying a surgical dressing such as a gauze pad or compress, either treated or untreated. These individually packaged adhesive tape carried dressings are widely used domestically and for first aid purposes and are usually self-applied. Such being the case, it is necessary that the dressing be easily removed and applied with a minimum of dexterity and with little exposure of the dressing *per se* prior to application. However, individually packaged surgical dressings of this type have heretofore been characterized by their complexity and difficulty of employment and application. The opening of the containing envelope is usually awkward, and separate operations are generally necessary to remove the adhesive and the protective materials before the dressing may be applied. Another disadvantage of the conventionally packaged dressing is its generally untidy arrangement from the standpoint of the number of separable elements which must ultimately be disposed of when the dressing portion is removed and applied.

It is thus a principal object of the present invention to provide an improved packaged surgical dressing.

Another object of the present invention is to provide an improved, individually packaged dressing including an adhesive tape carrying a pad and a disposable envelope protectively covering the dressing.

Still another object of the present invention is to provide an improved, individually packaged first aid dressing characterized by its simplicity and ease of application.

A further object of the present invention is to provide an improved, individually wrapped first aid dressing including a gauze pad mounted on a strip of adhesive tape and packaged in a disposable envelope and characterized in the ease of removal of the dressing from the envelope and its subsequent application.

A still further object of the present invention is to provide an improved, individually packaged first aid dressing including an adhesive tape carrying a compress or the like, and a sealed protective envelope enclosing the dressing and characterized by the dressing being easily removable from the envelope and readied for application, leaving the open envelope disposable as a single unit.

Other and further objects of the present invention will become apparent from a reading of the following description taken in conjunction with the accompanying drawing, wherein—

2

Figure 1 is a perspective view, partially broken away, of an improved individually packaged first aid dressing illustrated in closed condition and constituting a preferred embodiment of the present invention;

5 Figure 2 is a perspective view illustrating the application of the first aid dressing to a finger;

Figure 3 is a sectional view taken along line 3—3 of Figure 1.

The present invention broadly contemplates the provision of a packaged surgical dressing comprising a pair of superimposed panels separably sealed along their confronting edges to define an envelope, a strip of adhesive tape having a dressing positioned on the adhesive face thereof, said tape being disposed in said envelope and having an end thereof separably secured to an end of one of said panels, the interior face of one of said panels having a non-adherent surface confronting the adhesive surface of said tape.

In accordance with a preferred embodiment of the present invention, there is provided a long strip of a frangible material folded transversely at substantially its mid-point to define a hinge separating the strip into front and rear panels. An adhesive tape carrying a suitable dressing on its adhesive face has its opposite adhesive-free face superimposed upon the rear panel and is narrower than said panel. The free end of the rear panel is folded over to engage the end of the adhesive tape remote from the panel hinge. The inner face of the front panel is coated with a band of material non-adherent to the adhesive face of the tape. The two panels are sealed along their side edges and along a line inwardly of their free ends to form a sealed envelope having finger tabs, the non-adherent band confronting the adhesive face of the tape.

35 Referring now to the drawings which illustrate a preferred embodiment of the present invention, numeral 10 generally designates a strip of frangible material such as paper or the like provided with a transverse fold line 12 intermediate its ends defining a hinge and dividing the strip 10 into a front panel 14 and a rear panel 16. Strip 10 is coated or otherwise provided on its inner face with a thin layer 18 of a non-adherent material, said layer 18 extending to the ends of the strip 10 and being spaced from the side edges thereof to provide the non-coated longitudinal borders 20, 20. The non-adherent coating may be formed of polyethylene, polytetrafluoroethylene or other suitable substance which will not adhere to the adhesive surfaces of the conventional adhesive tapes.

35 The surgical dressing, *per se*, consists of a strip 22 of adhesive tape formed of a woven fabric or plastic backing having a layer of adhesive on a face thereof in accordance with conventional practice. A suitable dressing 24 which may be a gauze pad, compress or other dressing, either treated or untreated is positioned on the adhesive face of the tape 22. The tape 22 is no wider than the non-coherent coating 18 and is superimposed upon the rear panel 16 in registry with the coating 18 its adhesive free face confronting the panel 16 and the ends of the tape 22 extending substantially to the hinge 12 and to a point short of the free end of the rear panel 16. The free end of the rear panel 16 is folded over to engage the corresponding end of the tape 22 and to define a finger tab 26. The front and rear panels 14 and 16 are folded along the hinge 12 to confronting relationship, sandwiching between them the dressing carrying adhesive 22. The side edges of panels 14 and 16 are sealed to each other by a suitable cement or in any other conventional manner and the portions of panels 14 and 16 remote from hinge 12 are likewise sealed to each other along a line spaced from the free ends of the panels to complete an envelope fully enclosing the dressing carrying tape

22 and providing finger tabs 26 and 28 respectively. Tabs 26 and 28 facilitate the opening of the envelope, tab 26 engaging an end of the tape 22 as at 30, and being held following the opening of the envelope.

In employing the present improved packaged dressing, the finger tabs 26 and 28 are grasped between the thumb and index finger of each hand and spread to separate the panels 14 and 16 to open position, as illustrated in Figure 2 of the drawing. Tape 22 and dressing 24 will follow panel 16 by reason of the end of tape 22 being engaged by tab 26, the adhesive face of the tape 22 being easily separable from the non-adherent coating or surface 18. The dressing 24 is then applied to the injured area, such as the finger, and the unengaged end of the tape 22 is pressed against the area adjacent the injury to effect 15 securement thereof. Tab 26 will automatically open during application of tape 22 by pulling the envelope in a direction away from tape 22 to permit full detachment of the tape from the envelope and completion of the application of the tape and dressing. It is apparent from the above that opening of the envelope and application of the dressing can be performed in a single, continuous, simple motion.

While there has been described and illustrated a preferred embodiment of the present invention, it is apparent that numerous alterations and omissions may be made without departing from the spirit thereof. For example, the envelope may be completely formed of a non-adherent material such as polyethylene and the enclosure of the envelope effected by the usual heat sealing methods.

Having described my invention, what I claim and desire to secure by Letters Patent is:

1. A packaged surgical dressing comprising an envelope formed of a strip of frangible material forming first and second panels and folded along a transverse axis to define a hinge therebetween, said first and second panels being

arranged in confronting relationship and having their abutting side edges sealed to each other, a strip of adhesive tape carrying a dressing and disposed in said envelope, an end of said tape being removably secured to an end portion of one of said panels, a free end of one of said panels being folded over to engage a corresponding free end of said adhesive tape, said panels being sealed to each other along a line inwardly spaced from the ends of said panels remote from said hinge to seal said envelope and provide a pair of finger tabs, the inner face of said panel which confronts the adhesive face of said adhesive tape having a coating of a non-adherent material which extends between lines short of the edges of said panel.

2. A packaged surgical dressing comprising an envelope formed of a strip of frangible material forming first and second panels and folded along a transverse axis to define a hinge therebetween, said first and second panels being arranged in confronting relationship and having their abutting side edges sealed to each other, a strip of adhesive tape carrying a dressing and disposed in said envelope, an end of said tape being removed secured to an end portion of one of said panels, said panels being sealed to each other along a line inwardly spaced from the ends of said panels remote from said hinge to seal said envelope and provide a pair of finger tabs, the inner face of said panel which confronts the adhesive face of said adhesive tape having a coating of a non-adherent material which extends between lines short of the edges of said panel.
